MIRROR

Fred A. Krohm, Gary, Ind., assignor to Productive Inventions, Inc., a corporation of Indiana

Application June 16, 1948, Serial No. 147,001

Term of patent 14 years

(Cl. D14—6)

To all whom it may concern:

Be it known that I, Fred A. Krohm, a citizen of the United States of America and a resident of Gary, in the county of Lake and State of Indiana, have invented a new, original, and ornamental Design for a Mirror, of which the following is a specification, reference being made to the accompanying drawing, forming a part thereof.

The dotted line showing in Figures 1, 3, 4 and 5 is for illustrative purposes only.

I claim:

The ornamental design for a mirror, substantially as shown and described.

FRED A. KROHM.
